MOUNTING FOR CARBON COLLECTORS

Friedrich Leuchs, Nuremberg, Germany, assignor
to the firm C. Conradty, Nuremberg, GermanyApplication May 12, 1939, Serial No. 273,367
In Germany July 1, 1938

9 Claims. (Cl. 191—55)

A variety of mountings for carbon collectors, more particularly bow collectors, are known, the aim of which is, to give the carbon sliding element the greatest possible strength to resist bending and shocks. It has, for instance, already been proposed to slide a mounting on to the base of the carbon element and to fill the space between the mounting and the carbon element by a casting operation, or to enclose the whole base of the carbon element by a casting or spraying operation or, after coppering the carbon element, to solder it directly to the mounting. The methods enumerated have at least to some extent the effect of considerably increasing the resistance to fracture, but each of these methods involves more or less great difficulties for the manufacture, as a condition for an increase of the strength is as intimate and fissureless as possible an adhesion of the carbon element to the mounting. Carbon collector elements are of coarse ceramic products and as such are subject during firing to certain shrinkage conditions, the effect of which is, that the curvature of such collectors is not always the same, being in fact always slightly different. For this reason it is necessary to make a slip-on mounting for each individual carbon collector element and to fit it accurately to the curvature of the same. This applies even to the mounting which is cast round the carbon element and which, when the casting mould is suitably shaped, should accurately fit the carbon element. Since, however, the shrinkage of the cooling metal tends to crush the carbon element, an accurate fit of the mounting cannot be ensured even with this method. Attempts have been made to avoid this latter disadvantage, by inserting in the lateral shrinkage path at the base of the carbon element elastic pads which are intended to take up and annul the shrinkage pressure. This method is however also very complicated and can be carried out only with costly moulds and requires considerable manufacturing experience.

The invention provides a mounting which enables every bow collector of any curvature to be fitted in a simple manner with an absolutely securely seated mounting.

As most external mountings are slipped on in a dovetail-like manner and the mountings are made partly with and partly without reinforcing ribs, a dovetail mounting with a reinforcing rib shall now be described by way of example.

Fig. 1 is a side view of a drawn or cast profile mounting.

Fig. 2 is an end view thereof taken on section line X—X of Fig. 1.

Fig. 3 shows a side view of the mounting mounted upon a curved carbon collector element.

Fig. 4 is a sectional view taken upon the section line Z—Z of Fig. 3.

Fig. 5 is a cross-sectional view showing metal strips extending along the sides of the mounting, and

Fig. 6 is a side view illustrating the metal strips merging into the solid supporting elements.

A straight, drawn or cast profile mounting *a*, 10 the height *b* of the dovetail of which is smaller than the height *c* of the dovetail of the carbon collector element *d*, is first of all provided in the upper part, that is in the dovetail profile *b*, with notch-like saw cuts extending down to the base 15 plate *e*. The same procedure is followed as regards the reinforcing rib *f*, provided in this case, which is also cut with a saw down to the base plate *e*. This mounting which is in the first instance straight can then be slipped on to a carbon 20 collector element *d* of any curvature and will then, owing to its own elasticity fit closely against the base *k* of the bow-shaped carbon collector element. The notches *h* of the side walls will 25 open and the notches of the foot *f* will close, while the mounting is being slipped on. The slipped-on mounting *a* is thereupon encased by casting or spraying along the two notched side walls *b* with a metal in such a manner that the widened slits *h* produced by notching are filled 30 in and in addition are firmly connected together over the entire length of the collector. Thus there extend along the mounting proper strong metal strips *g* which on both ends of the carbon 35 collector element merge into solid supports *i* which are formed by casting or spraying.

The mounting has the advantage, that it is no longer put under pressure and crushed through the lateral shrinkage of the metal, as shrinkage transversely directed to the profile of the collector 40 element is made impossible by the slipped-on mounting *a*, whilst the laterally cast-on or sprayed part *g* of the mounting becomes firmly and well connected both with the carbon element and also with the slipped-on mounting, thus connecting the two with one another. The cast-on or sprayed end pieces *i* are securely and firmly connected with one another by the lateral cast-on or sprayed mounting strips *g* and these end pieces also connect the two lateral strips mechanically and electrically. The collector element is thus as it were embraced at its base both by the slipped-on mounting and by a cast-on or sprayed frame. In addition to this connection, however, there is the special advantage, that the 45 50 55

metal of the lateral strips *g*, applied by casting or spraying, combines more rapidly with the already slipped on mounting *a* than with the carbon element *d* and shrinks towards the metal. 5 The dovetail base of the carbon element is in this way firmly shrunk into the slipped on mounting.

Any very fine spaces left between the bottom *k* of the carbon collector element and the slipped-on mounting may be filled in by casting according to a known method. A mass for this purpose, which is preferably electrically conductive, will penetrate into all the finest interstices between the inside of the mounting and the carbon element and will connect them mechanically and electrically to form a single body. The mass used for this purpose may alternatively act as an insulator, as the current supply will nevertheless be maintained. Masses of this kind are for instance quickly setting cements and more particularly 10 sulphur. The reinforcing rib is welded, soldered or otherwise connected at its edge *l* which is closed by the rib being bent to a curve.

What I claim is:

1. An external mounting for carbon collector 25 elements of any curvature, having lateral holding strips for the carbon element, containing saw cuts or notches in the transverse direction to the axis of the curved collector element.

2. An external mounting for carbon collector 30 elements of any curvature, having lateral holding strips for the carbon element, containing saw cuts or notches in the transverse direction to the axis of the curved collector element, the height of the lateral holding strips being less than the height 35 of the base part of the carbon element.

3. An external mounting for carbon collector 40 elements of any curvature, having lateral holding strips for the carbon element, containing saw cuts or notches in the transverse direction to the axis of the curved collector element, and having a reinforcing rib which is provided before the 45 mounting is slipped on to the carbon element with saw cuts or notches.

4. An external mounting for carbon collector 45 elements of any curvature, having lateral holding strips for the carbon element, containing saw cuts or notches in the transverse direction to the axis of the curved collector element and having metal applied by a casting or spraying operation 50 to the mounting after it has been slipped on to the curved carbon element along the lateral holding strips so as to extend upwards to the top of the base portion of the carbon element and downwards below the bottom edge of the mounting.

5. An external mounting for carbon collector

elements of any curvature, having lateral holding strips for the carbon element, containing saw cuts or notches in the transverse direction to the axis of the curved collector element and having metal applied by a casting or spraying operation 5 to the mounting after it has been slipped on to the curved carbon element along the lateral holding strips so as to extend upwards to the top of the base portion of the carbon element and downwards below the bottom edge of the mounting. 10

6. An external mounting for carbon collector 15 elements of any curvature, having lateral holding strips for the carbon element, containing saw cuts or notches in the transverse direction to the axis of the curved collector element and having metal applied by a casting or spraying operation 20 to the mounting after it has been slipped on to the curved carbon element along the lateral holding strips so as to extend upwards to the top of the base portion of the carbon element and downwards below the bottom edge of the mounting, and at the two ends of the mounting to form end supports for the carbon element.

7. An external mounting for carbon collector 25 elements of any curvature, having lateral holding strips for the carbon element, containing saw cuts or notches in the transverse direction to the axis of the curved collector element, and having a reinforcing rib which is provided before the 30 mounting is slipped on to the carbon element with saw cuts or notches, the saw cuts or notches being connected again, after the mounting has been slipped on, by welding.

8. An external mounting for carbon collector 35 elements of any curvature, having lateral holding strips for the carbon element, containing saw cuts or notches in the transverse direction to the axis of the curved collector element, and having a reinforcing rib which is provided before the 40 mounting is slipped on to the carbon element with saw cuts or notches, the saw cuts or notches being connected again, after the mounting has been slipped on, by soldering.

9. An external mounting for carbon collector 45 elements of any curvature, having lateral holding strips for the carbon element, containing saw cuts or notches in the transverse direction to the axis of the curved collector element, and having a reinforcing rib which is provided before the 50 mounting is slipped on to the carbon element with saw cuts or notches, the saw cuts or notches being connected again, after the mounting has been slipped on, by metal being applied to the rib by a casting or spraying operation.
